UNITED STATES PATENT OFFICE.

FRED FERRAND, OF SOUTHPORT, ENGLAND.

MACHINE FOR SPINNING YARN.

Application filed July 22, 1925, Serial No. 45,210, and in Great Britain July 26, 1924.

This invention has reference to machines for spinning yarn.

Proposals have already been made to provide in a spinning machine a plurality of "lines" of drafting rollers in addition to the usual "lines" of drafting rollers, for the purpose of effecting by means of said additional rollers the drafting of the roving usually effected in a roving machine, and in this way rendering the employment of a roving machine unnecessary. In the said proposals the additional "lines" of drafting rollers were mounted side by side in horizontal alignment or inclined to the horizontal in alignment with or similarly to the usual "lines" of drafting rollers of the machine. With such arrangement of additional drafting rollers difficulty was experienced in getting short fibres to enter the "nips" of the rollers and it was found necessary to provide rollers for supporting the roving between pairs of adjacent drafting rollers, and in the end the arrangement was not successful in practice.

The object of this invention is to provide an improved arrangement of additional drafting rollers in mules, ring, and other machines for spinning yarns, whereby to effect in a practical and successful way in such machines the drafting of the roving usually effected in roving and/or intermediate machines.

According to this invention the "lines" of additional drafting rollers are arranged one above the other in more or less vertical alignment, instead of as hitherto proposed.

In the accompanying drawings Fig. 1 is an end elevation and Fig. 2 is a front elevation of one arrangement of drafting rollers in accordance with the invention.

Referring to the drawings, 4, 5 and 6 are the usual "lines" of drafting rollers of a mule, ring or other spinning machine.

At the rear of the rollers 4, 5, 6 additional "lines" of drafting rollers 7, 8 and 9 are arranged above one another.

The several "lines" of usual and additional rollers are driven at different speeds as is customary by any suitable means. Conveniently, and as illustrated, the shaft of the bottom rollers of the front "line" 4 is positively driven and has mounted on it a gear wheel 10 which drives a gear wheel 11 on a shaft mounted in a bracket 12. The said shaft also carries a gear wheel 13 which gears with a wheel 14 on the shaft of the bottom rollers of the rear usual "line" 6. On the latter

shaft are also two gear wheels 15, 16. The wheel 15 gears with a pinion 17 which in turn gears with a gear wheel 18 on the shaft of the bottom rollers of the middle "line" 5. The wheel 16 gears with a pinion 19 which in turn gears with a wheel 20 on the shaft of the bottom rollers of the additional "line" 7. The wheel 20 gears with a wheel 21 on the shaft of the bottom rollers of the "line" 8 which in turn gears with the wheel 22 on the shaft of the bottom rollers of the "line" 9. Thus the bottom rollers of the "lines" 4, 5, 6, 7, 9 all rotate in the same direction and the bottom roller of the "line" 8 rotates in the opposite direction. The top rollers of the several "lines" are rotated by friction from their bottom rollers in the usual way. By substituting for the gear wheel 13 wheels having different numbers of teeth the speed of the "lines" of rollers 5, 6, 7, 8, 9 relatively to the "line" of rollers 4 may be varied as required. The "lines" of rollers 7, 8, 9 are conveniently mounted in bearings supported by brackets 24.

The roving 23 passes into the "nip" of the uppermost "line" of additional rollers 9 from the rear and from such rollers it passes to the "nip" of the middle "line" 8 at the front, whence it passes to the "nip" of the "line" of the lowermost additional rollers 7 at the rear.

After issuing from the rollers 7 the roving passes to and through the "lines" of rollers 6, 5, 4 in the ordinary way.

With the described arrangement of the additional "lines" of rollers 7, 8 and 9 the roving is in contact with the rollers over a larger proportion of their circumferences than in the previous proposed arrangement before referred to, it is found that short fibres have a tendency to cling towards the upper rollers of the "lines" and are guided into the "nips", the stretches of the roving between the "lines" 9 and 8, 8 and 7, and 7 and 6 are substantially vertical and do not require to be supported, and it is possible in a spinning machine to draft and spin from a slubbing roving thus dispensing with the necessity of drafting the roving in intermediate and roving frames. Further, as no twist is imparted to the roving between the "lines" of rollers 9 and 4, the twist originally in the roving is practically eliminated by the time the drafted roving issues from the rollers 4 and the fibres are practically parallel.

Although I have described and illustrated the provision of three additional "lines" of

drafting rollers, it will be understood that I may employ any other suitable number of additional "lines" of drafting rollers.

What I claim as my invention and desire to secure by Letters Patent is:—

1. In a spinning machine such as a mule or ring frame, in combination, a set of lines of drafting rollers, and a plurality of additional drafting rollers arranged in a substantially vertical tier and adapted to the passage therebetween of a roving.

2. In a spinning machine such as a mule or ring frame, in combination, a set of lines of drafting rollers, and a plurality of additional drafting rollers arranged in a substantially vertical tier and adapted to the passage therebetween of a roving, and means

for driving said rollers at progressively increasing speeds, but less than the speed of said first mentioned drafting rollers.

3. In a spinning machine such as a mule or ring frame, the combination of a plurality of drafting rollers and a plurality of other drafting rollers in substitute of a roving machine, and means for entering short fibres between the substitute rollers, comprising relatively large freely mounted follower rolls, and means for causing the roving to wrap around a substantial portion of the periphery thereof.

In witness whereof I have hereunto set my hand.

FRED FERRAND.
